PUMP

Edward J. Ruthman, Cincinnati, Ohio

Application May 8, 1940, Serial No. 334,007

5 Claims. (Cl. 103—87)

This invention relates to improvements in a pump, particularly a pump for circulating or pumping metals when in the hot molten state, such as molten solder, molten babbitt, etc.

One of the principal objects of this invention is the provision of a pump, as above identified, in which means are provided for maintaining the pump shaft in a cool condition at all times to prevent the transmission of heat to the motor and parts associated therewith.

Another object of this invention is the provision of a pump for circulating molten metal, which is relatively inexpensive to produce and is highly efficient in operation.

Another object of this invention is the provision of a pump, for the purpose above specified, which is relatively simple in construction and operation.

Other objects and advantages of the present invention should be readily apparent by reference to the following specification, considered in conjunction with the accompanying drawings, forming a part thereof, and it is to be understood that any modifications may be made in the exact structural details there shown and described, within the scope of the appended claims, without departing from or exceeding the spirit of the invention.

In the drawings:

Fig. 1 is a front elevation of the pump, embodying the improvements of this invention, with a portion of the tank broken away.

Fig. 2 is a view taken at right angles to Fig. 1 and as seen from the lefthand side of said Fig. 1.

Fig. 3 is a horizontal sectional view taken on line 3—3 of Fig. 1.

Fig. 4 is a horizontal sectional view taken on line 4—4 of Fig. 2.

Fig. 5 is a horizontal sectional view taken in a plane below that of Fig. 4 on line 5—5 of Fig. 2.

Fig. 6 is a horizontal sectional view taken on a plane below that of Fig. 5 on line 6—6 on Fig. 2.

Fig. 7 is a vertical sectional view through the pump and motor shaft taken on line 7—7 on Fig. 1.

Fig. 8 is a horizontal sectional view through the pump taken on line 8—8 on Fig. 1.

Fig. 9 is an enlarged fragmentary elevational view of a portion of Fig. 1, showing a modification in the cooling mechanism.

Fig. 10 is a horizontal sectional view taken on line 10—10 on Fig. 9.

Fig. 11 is a vertical sectional view taken on line 11—11 on Fig. 9.

Throughout the several views of the drawings similar reference characters are employed to denote the same or similar parts.

As was pointed out above, this invention pertains to a pump and associated mechanism for pumping or circulating hot molten metals, such as solder, babbitt and the like. One of the uses for this mechanism is in the manufacture of honeycombed radiators, such as the radiator of automobiles and the like, or in fact any place where it is desired to produce a solder seam in connecting parts of thin metal sheets. Also useable in die casting.

Specifically referring to the drawings, the pump 15 of this mechanism comprises an electric motor 15 from which projects the motor shaft 16. The lower end of the motor shaft 16 is received in a pump housing 17. The pump housing 17, see Figs. 7 and 8, encloses an impeller 18 carried by the lower end of the shaft 16. The upper and lower ends of the housing 17 are closed by cap plates 19 and 20, each provided with an aperture or eye 21 for supplying the interior of the housing 17. Extending from one side of the housing, preferably tangentially thereof, is a discharge port 22 to which is connected in any suitable or desirable manner the discharge pipe or conduit 23.

Integral with and extending upwardly from the cap plate 19 is a casting or connecting housing 24, which comprises a pair of upright arms 25 and 26, terminating at their upper ends in a flange 27. The flange 27 has centrally thereof an aperture 28 through which the motor shaft 16 passes. Secured to the outer surface of the flange 27 is a short spacer housing 29 comprising arms 30 and 31 connecting flanges 32 and 33. The flange 32 is provided with a counter bore for an anti-friction bearing 34 for the shaft 16. Contacting with the flange 33 is the lower end of the motor 15.

Suitable bolts 35 are employed for securing the pump housing 17, housing casting 24, spacer housing 29 and motor 15 to one another to form a unit and vertically position the motor with respect to the pump. Secured to shaft 16 between the arms 25 and 26 are a plurality of fans 36, each of which comprises a disc 37 having upstanding therefrom fan blades 38 and a sleeve 39. Each of these fans is located in a passageway 76 formed across the motor shaft by a plurality of fins 77, one fin being located above each fan 36, and the fins being cast integral at diametrical points with the vertical housing arms 25 and 26. These fans act for circulating air through the passage-

ways 16 around the shaft 16 and thereby dissipate heat which would have a tendency to follow the shaft to the motor.

In order to support and position the motor, use is made of a frame, comprising a foot 40 secured in any desirable manner, such as by bolts 41 to the top plate 42 of a tank 43. The tank 43, it will be appreciated, is arranged to receive heat for melting metal therewithin. Rising from the foot 40 is a pair of arms 43 and 44, suitably braced as at 78 throughout their length. Projecting forwardly from said arms, at their upper ends, is a pair of guides 45 and 46, each provided with a suitable guiding aperture 47 for guide rods 48 and 49. The guide rods 48 and 49 have their ends threaded into ears 50 and 51 projecting laterally of the motor 15. Secured to the upper ends of the guide rods 48 and 49 respectively, are cables 52 and 53, each passing around a pulley 54 and 55 rotatively mounted at the forward ends of projections 56 and 57 extending from the uppermost brace 78 of frame arms 43 and 44. The free ends of the cables 52 and 53 are attached to a counterweight 58 adapted to operate between the pulleys 54 and 55 and the motor 15, as will later be made clear.

Forwardly of the pump supporting frame, the tank top 42 is provided with an opening 59 normally closed by a pair of plates 60 and 61. The plates 60 and 61 have their meeting edges recessed as at 62 and 63 to accommodate the housing arms 25 and 26 and shaft 16, and to substantially completely close the opening 59 around these parts so as to prevent loss of heat from the tank and splashing of molten metal. The plates 60 and 61 are retained within the opening 59 by a supporting ledge 79 secured to the under surface of the tank top 42 around said opening. To one side of the tank opening 59, the tank top 42 is provided with a recess 64 through which the discharge pipe or conduit 23 from the pump extends.

The operation of this mechanism is as follows:

The metal is maintained in a molten state to a height approximately as indicated at 65 in Fig. 1, leaving a space above the metal and below the tank top, indicated by the reference numeral 66, of an amount to accommodate the housing 17 above the molten metal. In order to insert the pump within the tank, the plates 60 and 61 are removed and the pump disposed below the tank top, whereupon the plates 60 and 61 are replaced to closely engage the arms 25 and 26 and shaft 16. In order to lower the pump into the molten metal, it is only necessary to vertically downwardly actuate same to a point below the top of the molten metal 65. Rotation of the motor 15 thereupon circulates the molten metal supplied to the pump housing by eyes 21 through the discharge conduit 23. Rotation of the motor 15 and its shaft 16 immediately causes operation of the fans 36 for maintaining a cooling flow of air around this shaft and stopping the travel of the heat upwardly thereof.

When it is desired to stop the flow of the molten metal, the pump and parts connected therewith, while the motor is still driving same, are raised to a position for placing the pump above the molten metal high line 65 so that the pump may discharge itself and prevent any metal from remaining within the pump to freeze the pump when the metal congeals.

From this, it will be seen that there has been provided a pump for circulating molten metal and in which the metal is discharged from the

5 pump prior to the cooling of the metal to the point of freezing the pump impeller 18. At the same time, there has been provided a pump which will maintain the pump shaft in a cool state while the pump is within the hot molten metal.

In order to further cool the pump shaft and to provide a definite band or zone to interrupt the heat flow, use is made, as shown in Figs. 9, 10 and 11, of a water jacket in place of the air cooled zone at the short connecting housing 29. This water jacket comprises a circular water tight casting 67, having at diametrically opposite sides threaded apertures 68 and 69, respectively for supply and discharge pipes or conduits 70 and 71, the former of which is connected with a suitable tap, while the latter is connected with a sewer or cooling chamber. The lower end or bottom 72 of the casting 67 is counterbored to receive the anti-friction bearing 34 and is provided with tapped bosses 73 projecting interiorly of the casting. The top 74 of the casting is likewise provided with interiorly projecting tapped bosses 75. The bosses 73 and 75 each receive suitable cap screws or bolts 35 for connecting the motor 15 thereto, as well as connecting the housing 24 thereto, all as above described in making a unitary assembly of the pump 17 and motor 15.

30 The operation of the modified construction in Figs. 9, 10 and 11 is the same as that above described, except that instead of depending solely on the circulation of air for keeping the motor shaft cool, this air cooling is supplemented by the water jacket 67 and the flow of water through this jacket in maintaining the shaft in a cooled condition.

What is claimed is:

1. In a pump of the class described, the combination of a pump unit, a motor unit, means spacedly securing the pump and motor unit to one another, including a pair of spaced arms, means connecting said arms and forming passageways between the arms located at spaced points along the spacing means, a shaft between the motor unit and pumping unit, and a plurality of fans on said shaft, each located in a passageway.

2. In a pump of the class described the combination of a pump housing encircling an impeller and having its sides open, a closure plate for each open side of the pump housing, a motor, means for connecting the pump housing and motor comprising a pair of spaced arms having their one ends integral with one of the closure plates and extending therefrom, means for connecting the other ends of the arms, and a water jacket casing having one side connected with the arms connecting means and the other side connected with the motor, and a motor shaft extending through the water jacket and between the spaced arms, said arms providing for air passage therebetween across the shaft.

3. In a pump of the class described the combination of a pump housing encircling an impeller and having its sides open, a closure plate for each open side of the pump housing, a motor, means for connecting the pump housing and motor comprising a pair of spaced arms having their one ends integral with one of the closure plates and extending therefrom, means for connecting the other ends of the arms, and a water jacket casing having one side connected with the arms connecting means and the other side connected with the motor, a motor shaft extending

through the water jacket and between the spaced arms, additional means carried by said arms between the housing closure plate and the arms connecting means for forming passage ways transversely of the shaft and located at spaced points therealong, and a plurality of fans on said shaft, each located in a transverse passage way.

4. In a mechanism of the class described for circulating molten metal, comprising a tank having a top and containing molten metal, a pump adapted to be submerged in the molten metal, a motor for driving the pump and located above the tank top when the pump is submerged, spacing means located partly above and partly below the tank top for connecting the motor and pump, a shaft between the motor and pump and disposed centrally of the spacing means, said spacing means including a pair of spaced arms, means for connecting the arms at spaced point above the tank top when the pump is submerged to form air passage ways transversely of the shaft, and a plurality of fans carried by the shaft one in each transverse air passage way for causing an air circulation therethrough.

5. In a mechanism of the class described for circulating molten metal, comprising a tank having a top and containing molten metal, a pump adapted to be submerged in the molten metal, a motor for driving a pump and located above the tank top when the pump is submerged, spacing means located partly above and partly below the tank top for connecting the motor and pump, a shaft between the motor and pump and located centrally of the spacing means, said spacing means including a pair of spaced arms extending from the pump and having their ends, remote from the pump, connected to one another, and a water jacket casing having one side connected to 10 the arms connecting means and the other side connected to the motor, additional means connecting the arms at spaced points between the tank top and the upper ends thereof to form air 15 passage ways transversely of the shaft, and a plurality of fans carried by the shaft one in each air passage way for causing an air circulation 20 therethrough.

EDWARD J. RUTHMAN.
